SAFETY CLOSURE FOR LETTERS

Albert Schülze, Neustadt-on-the-Tafelfichte,
CzechoslovakiaApplication June 30, 1932, Serial No. 620,139
In Czechoslovakia February 22, 1932

2 Claims. (Cl. 229—68)

The present invention relates to safety closures for letters.

The principal object of the invention is to provide means for the safe closing of letters by which letters of any kind can be closed with absolute certainty in every respect in such manner that a letter cannot be opened without damage occurring, whilst any damage which may arise is irreparable and the effect of such damage on the letter is perceptible at the first glance.

A further object of the invention is to provide sealing means, by the use of which the parts of the letter or letter card are closed or fastened to one another and their envelope or covering at folded-over corners or sides either individually or in groups.

Some preferred methods of carrying the invention into practice are illustrated by way of example in the accompanying drawing in which:

20 Fig. 1 shows an unfolded sheet of letter paper constituting a so-called letter card adapted for employment without an envelope,

Fig. 2 shows the aforesaid letter card after it has been folded,

25 Fig. 3 shows the letter card after it has been closed by adhesive and sealed,

Fig. 4 shows a letter arranged in an ordinary commercial envelope,

Fig. 5 is a cross section of Fig. 4 taken on the 30 line V—V,

Fig. 6 is a longitudinal section of Fig. 4 taken on the line VI—VI.

Fig. 7 shows the arrangement of a letter within an envelope of a particular form adapted to enable the sealing means to be applied at one corner,

Fig. 8 shows an arrangement of a letter in an envelope which is particularly adapted for the application of sealing means on one side,

Fig. 9 shows an arrangement of a letter containing valuable enclosures within a protecting sheath, and

Fig. 10 shows a section of the sheath taken on line X—X of Fig. 9.

Referring to the drawing:

45 The letter card illustrated in Figs. 1—3 is provided over the half of two adjacent edges b and c with adhesive flaps K₁ and K₂, is twice folded, stuck down by means of the adhesive flaps and finally stuck down at one edge by means of a 50 closure strip S, the two ends of which are sealed by means of a sealing member P i. e. an eyelet, rivet, or the like which passes right through.

Fig. 4 illustrates the application of the invention to commercial letters. The singly or doubly folded letter is inserted in the envelope in

such manner that one folded edge B₁ is located at the opening side. The letter is then closed in the ordinary way and the sealing member P is passed through the envelope and the letter at the lower edge a, or laterally opposite to the laterally located folded edge B₂ as shown at P₁, or in the corner formed by the said two edges a, d. The closure flap c' is preferably so shaped (see Fig. 4), c'', that it can likewise be gripped by the sealing member P. By constructing the envelope of suitable shape it is, however, also possible to grip all the four flaps of the envelope and all the sheets of the letter by means of the sealing member (see Figs. 7 and 8). B₁ and B₂ denote as before the folded edges of the letter, a, b, c, d are the edges of the envelope and a', b', c', d' are the corresponding flaps of the envelope.

In the constructional form shown in Fig. 7 the sealing is effected at the corner and in the constructional form shown in Fig. 8 at the side opposite to the opening of the envelope. The closure grips all the parts of the envelope and of the letter when the letter is located so that one folded edge B₁ is located at the opening side c and the laterally adjacent folded edge B₂ is located opposite to the place where the sealing member is applied.

For letters containing valuable enclosures a special protective member E is provided which consists of a sheath comprising an upper and a lower wall and having adhesive reinforcing strips on the sides through which the sealing member is to pass, the said strips being adapted to prevent the sealing member from damaging the valuable enclosures, and being preferably formed by sticking the upper and lower walls of the sheath together over a short width at the sides and bottom. The letters may be sealed by means of sealing members at one or more sides, the strips at the sides of the sheath being gripped by means of the sealing members. The sealing can, however, also be effected at all sides by the use of a further sealing member P' applied at the opening side, if in doing this damage to the valuable enclosure located in the protective sheath can be avoided.

The envelopes according to Figs. 7, 8 and 9 may also be employed without being gummed together inasmuch as by the employment of a sealing member it is rendered quite impossible to open 50 the letter without destroying the envelope or the sealing member respectively.

When envelopes which are not gummed down are employed it is only necessary to fold over the flaps in the correct order of succession. The lat- 55

eral flaps are first folded over, then the lower flap and finally the upper flap.

Letters closed in the above described manner according to the invention can only be opened after removal of the sealing members, which latter may be provided with embossed matter, initials, crests, trade marks or the like. The letter may be opened by removing or cutting off the sealing members.

10 The advantages of the safety closure for letters according to the invention will be obvious. The secrecy of the letter and any business matter contained therein is ensured as is also the safety of the contents of letters containing valuable enclosures and registered letters, so that in the latter cases the enclosures may be of greater value than hitherto. Moreover, in the closing of ordinary letters greater cleanliness, simplicity and saving of time during the closing operation are obtained.

15 20 I claim:

1. A safety closure for letters, more particularly letters containing valuable enclosures, comprising in combination: an envelope having a plurality

of end and side flaps; a separate protecting sheath for the reception of the letter, said sheath being removably arranged within said envelope; reinforcing strips at the sides and bottom of said sheath; and sealing means passing through all the flaps of said envelope and through said reinforcing strips, whereby said sheath and said envelope are fastened together.

2. A safety closure for letters, more particularly letters containing valuable enclosures, comprising in combination: an envelope having a plurality of end and side flaps; a separate protecting sheath for the reception of the letter, said sheath having a front wall and a back wall and being removably arranged within said envelope; reinforcing strips at the sides and bottom of said sheath formed by sticking the upper and lower walls of the sheath together over a short width at the sides and bottom; and sealing means passing through all the flaps of said envelope and through said reinforcing strips, whereby said sheath and said envelope are fastened together.
